UNITED STATES PATENT OFFICE.

ROY COON, OF WINDSOR, COLORADO.

ROAD DRAG.

Application filed February 18, 1924. Serial No. 693,500.

To all whom it may concern:

Be it known that I, Roy Coon, a citizen of the United States, residing at Windsor, county of Weld, and State of Colorado, have 5 invented certain new and useful Improvements in Road Drags; and I do declare the following to be a full, clear, and exact description of the invention, such as will enable others skilled in the art to which it applies 10 to make and use the same, reference being had to the accompanying drawings, and to the characters of reference marked thereon, which form a part of this specification.

15 This invention relates to road drags and has particular reference to improvements in the adjusting means therefor.

It is customary, where dirt roads are in use, to drag the same after a rain has moistened the surface of the road. The purpose 20 of the dragging is to make the road smooth and to give it a convex transverse curvature.

For the purpose of properly smoothing the road surface, drags of various kinds 25 have been invented, some of which have been manufactured and sold in considerable numbers.

30 My improved drag, briefly described, consists of two drag sections, each of which comprises three or more scrapers pivotally connected at their ends to longitudinal bars so that each section may be made into a rectangle or into a parallelogram with alternately acute and obtuse angles. The trans- 35 verse angular scrapers are also pivoted so as to rotate on an axis parallel with the plane of the section and are yieldingly held in adjusted position about this axis. The two sections are connected at one end by a short link and at the other end by a longer link so that they are angularly related to each other. The long link is adjustable so 40 that the angle between the sections can be made as large as desired so as to fit the drag to roads of different widths.

45 My invention can be best described when reference is had to the accompanying drawings in which the present preferred embodiment thereof is illustrated, and in which:

50 Fig. 1 is a perspective view of the drag in assembled position and adjusted for moving the dirt towards the center to form a crown or convex surface;

55 Fig. 2 is a section taken along line 2—2, Fig. 1;

Fig. 3 is a plan view showing the drag

reversed for use in flattening a road surface;

Fig. 4 is a section through one of the scrapers, said section being taken substantially on line 2—2, Fig. 1, and shows the scraper tilted; and

Fig. 5 is a section taken on line 5—5, Fig. 3.

Numeral 1 designates the longitudinal bars, of which there are two to each section. Pivotally connected to these bars are pivots 2, each of which has an enlarged head 3 which is provided with a transverse opening within which is journaled the end 4 of the axle member 5 (Figs. 4 and 5). The axle members 5 are secured to the ends of the angles 6 in the manner shown in Fig. 5. To the vertical flange of each angle 6 I secure a steel plate 7. At a point substantially midway between the ends of angles 6, I secure arms 8 in the manner shown in Figs. 2 and 4. Parallel bars 9 are pivotally connected to arms 8 by means of bolts 10. The upper ends of arms 8 have openings for the reception of a rod 11. Pins 12 pass through the bar and form a stop for the arms 8. Surrounding bar 11 and abutting arms 8 are helical springs 13 that are held under compression by means of the pins 14. Pivot- 85 ed to one of bars 9 at point 15 is a lever 16. This lever has a longitudinal slot for the reception of a bolt 17 which is secured to the rod 11. A notched segment 18 is secured at its ends to one of bars 9 and the notches co- 90 operate with the plunger 19, which passes through openings in guides 20 and is forced downwardly by means of a spring 21. It is now evident that by moving the lever 16 about its pivot 15, the angular relationship 95 of the angles 6 and the bars 1 may be adjusted to the extent desired and held in adjusted position.

The springs 13 permit the transverse members to yield if they should strike a stone or if for any other reason they should be subjected to a severe strain. A diagonal bracing member 22 is connected with one of the pivots 2 and has a slot 23 that connects with another of the pivots 2. By 100 means of this diagonal bar, the horizontal angular relation between the bars 1 and the angles 6 can be adjusted and held in adjusted position.

Secured to each of the inner bars 1 is a 110 pair of lugs 24 between which is pivoted one end of the toggle member comprising

members 25 and 26. These members have each a plurality of holes 27 for the reception of a pivot pin 28. By placing pin 28 in different holes, the length of the link can be adjusted to suit the requirements of the case. A pin 29 in the end of member 25 prevents the link from collapsing when subjected to pressure. Ears 30 and 31 are secured to the front end of each section and to these the chain 32 is connected in the manner shown in Fig. 1. The chains serve to connect the drag to the tractor or with the teams as the case might be.

It sometimes happens that the roads become too convex and that it is necessary to flatten them. When this is the case the sections are transposed, the short link is moved to the front end of the sections in the manner shown in Fig. 3 and the long, adjustable link is moved to the rear and connected to the lugs 24, which have been provided for this purpose. When the sections are connected as shown in Fig. 3 and are pulled along the road, they will move the ground outwardly, thereby flattening the road.

When the drag is to be moved along the road without doing any appreciable amount of work, the long link is removed and the diagonal adjusting bar 22 loosened so as to permit the sections to be collapsed as much as possible.

If there should be a stone embedded in the road surface or some other solid body, the scrapers, as they strike the same, will yield owing to the action of spring 13, and permit the scraper to yield.

By means of the diagonal bar 22, the angular relation of the scrapers to the bars 1 can be adjusted in the plane of the section and by means of the lever 16, the angular relation of the scrapers can be adjusted about their axes.

Having now described my invention, what I claim as new is:

45 1. A road drag section comprising a pair of parallel bars, said bars having pivots connected thereto at spaced intervals, each of said pivots having transverse openings forming bearings, angular scraper members 50 pivotally mounted in said bearings, and means for adjusting the angular relationship of the bars and scrapers in the plane of the section, means for adjusting the

scrapers angularly in said bearings, said last-named means having resilient means 55 for yieldingly holding the scrapers in adjusted position.

2. A road drag section comprising, in combination, a pair of spaced parallel bars provided with spaced openings for the reception of pivot members, pivots in said openings, each pivot having an enlarged portion provided with a transverse opening for the reception of an axle member, angular scraper members having their ends attached 65 to the axle members, means for changing the angular relationship of the scrapers and the parallel bars in the plane of the sections, means for simultaneously rotating said scrapers about said axle members, and 70 resilient means for permitting each scraper member to rotate about its axis to a limited extent.

3. A road drag section comprising a pair of spaced bars having spaced openings, 75 pivots rotatably mounted in said openings, said pivots having their lower ends enlarged and provided with transverse openings forming bearings, a plurality of parallel 80 angular scrapers having their ends provided with axle members adapted to enter said bearings, a diagonal brace member extending from one of said bars to the other, said member having a longitudinal slot, a bolt secured to one of said bars and extending 85 through the slot for clamping the brace member to the bar, each of said scraper members having an arm secured thereto and extending upwardly therefrom, said arms having openings in their upper ends 90 for the reception of a bar, a pair of bars pivotally secured to the arms at a point near the scrapers, a handle pivotally connected to said bars and also connected to the bar passing through the opening in the 95 upper ends of said arms, a stop (12) on said last-named bar for cooperating with said arms to prevent movement thereof in one direction, a spring on the bar, one end engaging one side of one of the arms and 100 the other end engaging a stop, and means for holding the lever in any adjusted position.

In testimony whereof I affix my signature.

ROY COON.
